UNITED STATES PATENT OFFICE.

DAIJI YAMADA, OF SANTA ANA, CALIFORNIA.

ELECTRIC-LIGHT-ADJUSTING SOCKET.

1,114,089.

Specification of Letters Patent.

Patented Oct. 20, 1914.

Application filed November 17, 1913. Serial No. 801,414.

To all whom it may concern:

Be it known that I, DAIJI YAMADA, a subject of the Emperor of Japan, residing at Santa Ana, in the county of Orange and State of California, have invented a new and useful Electric-Light-Adjusting Socket, of which the following is a specification.

This invention relates to a socket for receiving and making electric connection with an electric lamp bulb, and provided with means for adjusting or regulating the intensity of the light furnished by said bulb, and the main object of the present invention is to provide an effective and simple device of this character which will provide for several different intensities of light.

Another object of the invention is to provide means for safeguarding the device against excessive use of current.

20 Other objects of the invention will appear hereinafter.

The accompanying drawings illustrate the invention, and referring thereto:

Figure 1 is a vertical section of the socket 25 with a portion of the bulb. Fig. 2 is a perspective view of the circuit controlling means with electric connections thereof shown diagrammatically.

The socket comprises an upper head 1 provided with a metallic shell 2, a cylindrical casing 3 connected to said shell 2, and a lower head 4 secured to the lower end of said casing. The shell 2 of the upper head 1 is bent inwardly over the upper head 1 and extended upwardly to form a neck 5 attached by screw 6 to a knob or support 7, the lower end of which extends within said neck. The knob 7 and head 1 are of insulating material and are bored as shown at 40 7' and 1' respectively for passage of the lamp cord indicated at 8, the two wires 11 and 12 of said lamp cord being bent under the head 1 and secured thereto by screws 13 and 14 which also serve to fasten in position 45 on said head, contact springs 15 and 16. The casing 3 is provided with ventilating perforations 10. Said casing is removably fastened to the shell 2 by screws 17 and the lower end of said casing is bent inwardly 50 around the lower head 4 and extended downwardly to form a sheath or housing 9 for the lamp socket proper. Said lamp socket proper consists of an outer screw-threaded socket ring 18 fastened by screws to the bottom of lower head 4 and adapted to make contact with the screw ring 20 on the lamp

bulb 21, and a central contact 22 on the lower head 4 adapted to make contact with the central contact 23 on the base of the lamp bulb. Said contact head 22 is formed as a 60 head of a metallic pin 24 having a screw-threaded portion 24' screwed in the lower head 4 and extending through the same, the upper part of pin 24 being cylindrical and engaging at its upper end with the contact 65 spring 15 aforesaid.

A spool 28 of insulating material is bored as shown at 27 to revolvably fit on the upper portion of the pin 24 and rests at its lower end on the lower head 4 on the socket. On 70 the upper end of this spool is secured a metal ring 29 which engages with the contact spring 16 aforesaid so as to maintain continuous contact therewith in the rotation of the spool. A contact spring 30 supported on 75 an insulating block 31 on the side of the casting 3 is connected by a wire 32 to the socket ring 18 and is adapted to engage with any one of a series of contacts 33^a, 33^b, 33^c, 33^d and 33^e on the upper disk of the spool 28. 80 Said contacts may consist of screws screwed into the said upper member of the spool and are connected respectively to resistances wound on said spool as hereinafter set forth. Spool 28 is provided, preferably at its lower 85 head, with a gear wheel 35 consisting, for example, of a circular band secured to said lower head and having crown teeth or serrations 35' on its upper edge. A shaft 37 mounted in a bearing 38 on the side of casting 3 carries a pinion 39 engaging the gear 90 aforesaid, said shaft being provided with an operating button or handle 40, whereby said pinion may be rotated to turn the gear wheel 35 and the spool 28.

95 The spool 28 is wound with a series of resistance wires 36 of suitable conducting material, preferably insulated with asbestos. As indicated in Fig. 2, these resistance wires or sections of resistance are connected in 100 series, the first resistance section being connected at one end to the first contact 33^a on the upper spool head and being connected at its other end to the second contact 33^b; the second resistance being connected at one end to 105 the second contact 33^b, and at its other end to the third contact 33^c, and so on until the final contact is reached. A fuse wire 42 of suitable fusible material is connected to the first contact 33^a and to the contact ring 29 110 aforesaid.

The operation is as follows: When the

lamp is not in use the contact spring 30 is out of contact with all of the contacts 33^a etc., so that the circuit is interrupted. When it is desired to light the lamp, the knob or handle 40 is turned so as to rotate the spool 28 through the operation of gears 39 and 35, thereby bringing the first contact 33^a into contact with the spring 30, whereupon current will flow from the circuit wire 11 through contact spring 15, pin 24, head 22, through the lamp filament to contact rings 20 and 18 and by wire 32 to contact spring 30, contact 33^a, fusible wire 42 to contact ring 29 thence through contact spring 16 to the other circuit wire 12. The circuit so traced does not include any resistance except that of the lamp itself, so that maximum current will flow in this case and the lamp will be operated at its full intensity. By turning the knob 40 farther, the second contact 33^b is brought into contact with the contact spring 30 and the current will then pass as above traced until it reaches contact spring 30, whence it will pass to the second contact 33^b and thence through the first section of resistance wire 36 to contact 33^a from which it passes to the other side of the circuit as above traced. As one of the resistance sections 36 is now included in circuit, the amount of current passing through the lamp will be correspondingly diminished and the intensity of illumination will be decreased, and similarly by turning the knob 40 still farther, two, three or more of these resistance sections may be included in series in the circuit with the lamp, so as to decrease the illumination to any required extent.

What I claim is:

1. An electric lamp socket provided with means for attachment thereto of an electric lamp bulb and with connections for said bulb and for an electric supply circuit, a member rotatably mounted on said socket and provided with a series of resistance sections, contacts carried by said rotatable member and connected to said wires, a fixed contact coöperating with the aforesaid contacts, and electric circuit connections including said fixed and movable contacts for connecting one or more of said resistance sections in series with the electric lamp, according to the rotative position of said rotatable member, and means for rotating said rotatable member comprising a handle out-

side of the socket and connections between said handle and spool for rotating said spool by operation of said handle.

2. An electric lamp socket comprising a casing, a pin contained in said casing and supported thereon, a spool rotatably mounted on said pin, a series of resistance sections wound on said spool, a series of contacts on said spool connected respectively to said resistance sections, a contact spring mounted on said casing and adapted to coöperate with said contacts on said spool, electric supply circuit connections connected to the lamp and to said fixed contact for including one or more of said resistance sections in series with the lamp according to the rotative position of said spool, means for rotating said spool, comprising a gear member carried by said spool, a shaft rotatably mounted in said casing, a pinion carried thereby, engaging the aforesaid gear member, and a handle on said shaft.

3. An electric lamp socket comprising a casing provided at one end with two contact springs for connection respectively to the wires of an electric supply circuit, a pin extending centrally in said casing for engaging one of said contact springs, a spool rotatably mounted on said pin, a contact ring carried by said spool and engaging the other of said contact springs, a series of contacts carried by said spool and connected to said contacts, a fixed contact spring engaging the contacts carried by said spool, and contact means carried by said socket for engagement respectively with the terminals of an electric lamp bulb, electric lamp bulb, one of said contact means being connected to said pin, and the other of said contact means being connected to the aforesaid contact spring coöperating with the series of contacts on the spool, a gear member carried by said spool, a shaft rotatably mounted in said casing and provided with an operating handle, and a gear member carried by said shaft for engaging the aforesaid gear member on said spool.

In testimony whereof, I have hereunto set my hand at Los Angeles, California, this 7th day of November, 1913.

DAIJI YAMADA.
